STOKER

James Gunnell Malone, Tottenville,
Staten Island, N. Y.

Application December 27, 1933, Serial No. 704,211

20 Claims. (Cl. 110—45)

This application is a continuation-in-part of my application Serial No. 602,955 filed April 4, 1932 and entitled Stoker.

This invention relates to new and useful improvements in stokers for furnaces and in gas producers and the like.

The invention has for an object the construction of a stoker which is characterized by a grate, means for moving the grate to cause a crushing action in conjunction with an opposed surface such as the wall of a furnace, and means for simultaneously providing a continuous motion of the fuel bed to prevent clinkering.

Furthermore, as another object of this invention it is proposed to provide an annular ash conveying member with air passages for air, beneath said grate to cool the grate and to convey ashes.

Another object of this invention is to provide air seals within the mechanism to prevent air circulation up through the ash discharge space, and to allow ashes to fall freely without the interference of an adverse current of air. Furthermore, it is proposed to arrange the seals so as to prevent air from flowing up through the ash space and around the periphery of the grate, and force the air to flow up through parts around the hub of an eccentric of the device, thus efficiently cooling said parts and at the same time blowing ash away from the eccentric bearing surface.

A still further object of this invention is the construction of a device of the class described which is of simple durable construction, dependable in use and efficient in operation and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a device constructed according to this invention.

Fig. 2 is a fragmentary sectional view taken on the line 2—2 of Fig. 1.

Fig. 3 is a fragmentary horizontal sectional view taken on the line 3—3 of Fig. 2.

Fig. 4 is a fragmentary sectional view taken on the line 4—4 of Fig. 1.

Fig. 5 is a fragmentary sectional view taken on the line 5—5 of Fig. 4.

Fig. 6 is a fragmentary view similar to a portion

of Fig. 2 but representing a section taken on the line 6—6 of Fig. 1.

Fig. 7 is a plan view of the combination annular air distributor and ash conveyor used in the device, illustrated per se, and also shows the actuating eccentric.

Fig. 8 is a vertical sectional view of Fig. 7 taken on the line 8—8 of Fig. 7.

The structure, according to this invention, has a body 10 for placement in a furnace, indicated generally on the drawings by reference numeral 11. A filler 12 is shown interposed between the furnace and the body 10 providing a shelf upon which the ash may assume an inclined shape, indicated by reference numeral 13. This shelf 12 and ash deposit 13 are especially provided to act as a safety cushion for tramp iron, etc. The top of the fuel bed is indicated by reference numeral 14. The top of the body 10 is open and a fuel feed tube 15 extends through the body and has a vertical portion at the center of the body and a horizontal portion passing through the side of the body to the hopper as clearly shown in Fig. 4. The top of the vertical portion of the fuel feed tube 15 has a spherical zone seat 16.

An annular ash conveying member with air passages has an annular portion 17 and is rotatively mounted on a hub portion 18 of the vertical portion of the fuel feed tube 15. The annular ash conveying member with air passages 30 has an eccentric 19, eccentric on its outer face, air passages 20, and an ash supporting surface 21. The annular portion 17 is coaxially mounted with respect to the feed tube 15 and is supported in spaced relation thereto by means of a plurality 35 of radially extended arms or spokes 19' rigidly connected to the portion 17 and the eccentric 19 so as to form openings between these parts. The eccentric outer face of the eccentric 19 is of cylindrical shape but has its axis arranged at 40 an inclination as clearly illustrated in Figs. 6, 7 and 8. More particularly the axis of the cylindrical outer face of the eccentric 19 crosses the axis of the central opening in the eccentric at a point W which corresponds (see Fig. 6) with the common center of the spherical zones 16 and 25 and 29. To better understand this construction, the line X in Fig. 7, appearing in this figure as a point because seen in end elevation, represents the center of the opening in the eccentric 45 19, which corresponds with the line X in Fig. 8 also representing the axis of the feed tube 15. The point Y in Fig. 7 corresponds with the point Y in Fig. 8 and the distance between X and Y represents the eccentricity of the outer face of 50 55

the eccentric at the top of the eccentric. The line Z in Figs. 6 and 8 represents the axis of the cylindrical outer face of the eccentric 19, said line Z extending through the point Y and intersecting the line X at the point W. The point W corresponds with the common center of curvature of the spherical zones 16 and 25 and 29. A baffle portion 22 projects from the annular ash conveying member with air passages and serves to effectively separate the ash conveying portion from the air passage portion, the air passing therethrough acting to effectively cool the eccentric bearing surface.

A grate 23 is located above the annular ash conveying member and has a central fuel entrance passage 24 formed by a hub having a spherical zone portion 25 at its bottom engaging upon the spherical zone seat 16 and an outer portion 26 encircling the eccentric 19. The spherical zone portions 16 and 25 constitute a bearing for supporting the grate 23. The inner face of the portion 26 is cylindrical and has its axis corresponding with the axis of the grate and engages the outer eccentric face of the eccentric 19. The sectional view illustrated in Fig. 2 is taken upon the neutral plane 2-2 of Fig. 3 and for this reason the contacting faces of the eccentric 19 and the portion 26 are in the vertical and furthermore for this reason the thickness 30 of the walls of the eccentric 19 are identical. In Fig. 6 the section is taken upon a plane represented by the line 6-6 of Fig. 3, which is a plane giving the maximum tilt of the grate due to the eccentric 19. Rotation of the eccentric 35 19 causes the grate to move in a wobbling gyratory path and the grate itself is supported on spherical zones 16 and 25 to accommodate this wobbling gyratory motion. The grate itself will not rotate but the high and low points respectively will progress or revolve continuously around 40 during the gyratory motion. Expressed in different words the grate while standing still as far as rotation is concerned has a continuous eccentric wobble which moves around in a circle. The grate 23 has a plurality of air passage openings 27 extending from the top to the bottom and arranged over the conveying surface 21 and constitutes the fire bed area. The portion of the grate formed with the openings 27 is at an inclination downwards so as to form substantially 45 a frusto-conical surface, the purpose being to insure the proper passage of the ash as herein-after fully described, and also to oppose the inner wall 11^a of the furnace 11. During the wobbling gyratory action of the grate the material on the grate will be crushed against the wall 11^a by portions thereof moving towards the wall 11^a. This may be better understood by examining 50 Fig. 6, in which figure the frusto-conical surface is confined between the letters AB and CD. If the lines AB and CD were continued until they met in a point, a cone would be formed. Consequently, the annular surface AB and CD is frusto-conical. Material on the grate caught in 55 between this frusto-conical surface and the cylindrical surface 11^a during the gyrating of the grate, will be crushed. For example, one line of crushing will exist along the line EF. On this line several lumps of solid fuel such as coal or coke are shown extended along the line and indicated by reference numerals 13^a. The reason crushing takes place is that while this particular portion of the grate moves upwards, it also moves closer to the wall. In other words, the crushing 60 is due to the fact that the grate has a particular

gyratory motion. This gyratory motion may be defined as the motion which the frustum of a cone AB and CD would describe if the axial center line Z of the frustum of the cone were revolved on an imaginary conical surface having as its axis the line X and as its apex the point W. In order to obtain the desired motion it is necessary that the apex W of the imaginary conical surface be on the same side of the base of the frustum of the cone AB and CD as that of the apex of a cone having the frustum AB and CD. When so constructed the grate will progressively tilt so that when a side portion thereof is moved upwards it will simultaneously be moved towards the wall 11^a. Crushing then takes place. On the downward motion this portion of the grate will simultaneously move away from the wall 11^a so that the crushed material will settle down and be in position to be crushed again during the next cycle of operation of the 15 20 25

This particular gyratory motion must be distinguished from the gyratory motion in which a grate having a frusto-conical portion AB and CD is mounted upon the top end of a gyratory shaft. In this latter case the axis of the grate would revolve on an imaginary conical surface the apex of which is on the opposite side of the base of the frusto-conical shape. When thus arranged crushing will not take place because then, if a portion of the grate moves upwards, it simultaneously moves away from the opposed wall. Subsequently, when that portion moves downwards it moves towards the wall. Screen material 28 for preventing small particles of fuel from falling through the grate may be attached 30 35 40 45 50 55 60 65 70 75 80 85 90 95 100

A spherical zone shaped ash passage 29 exists between the periphery of the grate 23 and the top opening in the body 10. The adjacent surfaces of the grate (the edge thereof), and the top opening in the body 10 are substantially spherical zones having their centers of curvature W coinciding with the center of curvature W of the spherical zone seat 16 and the spherical zone surface 25. This arrangement serves to form an ash passage 29 of constant cross section between the body 10 and the grate irrespective of the position of gyration of the grate. This will be clearly understood by considering Figs. 2 and 6 and imagining the grate tilting first in one direction and then in the other on the spherical zones 16 and 25 and then bearing in mind that the adjacent spherical zone surfaces of the body 10 and the grate; that is, the walls of the spherical zone shaped passage 29, are on concentric circles with the centers coinciding with the centers of the spherical zones 16 and 25, and furthermore that motion takes place about these coinciding centers as an imaginary pivot point. This same condition holds true in all central vertical sections which may be cut through the axis of the grate. One advantage of maintaining the passage 29 constant between the grate and the body is that foreign matter such as tramp iron, slate, rock and other articles cannot become wedged in the passage 29 between the body and the grate and cause stresses and perhaps breaking of the device. If this passage 29 between the body and the grate varied during the gyratory motion it can easily be seen that if a foreign piece of matter were wedged in this opening the gyratory motion could not continue and if forced to continue something must break, either the foreign matter, or, if the foreign 75 80 85 90 95 100

matter is iron that would not break, then a part of the stoker. Another important advantage of keeping the passage 29 between the body and the grate constant during the gyratory motion is that 5 then this passage may be very small to allow the passage of ash only. If this passage 29 changed during the gyratory motion there would be a time when it is large and a time when it is small and consequently when the passage is large, large 10 pieces of ash and perhaps unburnt coal would pass through. Another advantage is that the eccentricity of the grate motion is not limited by this passage size at all.

An air seal 30 is formed between the periphery 15 of the portion 17 of the annular ash conveying member and the body 10, and particularly comprises flanges 31 and 32 projecting from the portion 17 and from the body 10 and extending towards each other so as to form the space 30 which 20 becomes filled with ashes or which may be filled with other material to produce the air seal. A fuel feed is associated with the fuel feed tube 15 and comprises, particularly, a fuel feed tube 15 from a fuel supply such as the hopper 34. The 25 fuel feed tube 15 is firmly supported within the body 10 by reason of a support bar 35 attached upon the side of the fuel feed tube and attached on the body 10. The screw 33 terminates at one 30 end at the portion where the fuel feed tube 15 turns upwards. The hopper 34 has a gate 37 normally extended over a side opening 38 in the hopper so as to form a part of the hopper wall and adapted to be moved into a position indicated by the dot and dash lines 39 to close the passage 35 through the hopper and simultaneously form an opening in the side of the hopper so that the interior is exposed. More particularly, a mechanism is provided for moving the gate as desired and comprises a pair of pins 40 projecting from the sides of the gate and engaging in vertical 40 grooves 41 formed in the hopper 34. A lug 42 projects from the gate 37 and is pivotally engaged by a lever 43 fixed at its lower end on a horizontal control rod 44 and to assume a position indicated by the dot and dash lines 43 which is the closed position. The shaft 46 of the screw 38 extends through the hopper and is connected with a drive as hereinafter further described.

A means is provided for revolving the annular ash conveying member and comprises a circular flange 47 projecting from the bottom of the portion 17 of the annular ash conveying member and formed with bevel teeth 48 meshing with bevel teeth upon a ring gear 49 rotative on the horizontal portion of the fuel feed tube 15. The ring gear 49 is also provided with spur teeth 50 meshing with a pinion 51 upon a drive shaft 52 projecting from the body 10.

An ash discharge is arranged in conjunction 50 with the annular ash conveying member, see Fig. 2, and comprises particularly a scraper element 53 projecting from the inner wall of the casing 10 and extending in the space above the ash conveying surface 21. This scraper is adapted to deflect the ash from the conveying surface 21 through an opening 54 in the side of the body 10. An ash cover 55 is attached upon the side of the casing 10 over the opening 54 to direct the ash downwards to an ash container 56. An ash conveyor is associated with the ash discharge and includes an air seal. More particularly, a transfer casting 57 is attached upon the ash container 56 and has a horizontal portion 58, an inclined portion 59, and a vertical portion 60. 70 A horizontal ash screw 61 is arranged upon the

shaft 52 and extends through the horizontal portion 58 of the transfer casting. A bevel gear 62 is attached upon the shaft 52 outside of the transfer casting and meshes with another bevel gear 63 on a shaft 64 extended through the vertical portion of the transfer casting. The portion 60 is not truly vertical but really at an inclination to the vertical as may be seen from inspecting Fig. 1 so that the ash is conveyed to one side for connection with a suitable discharge. A substantially vertical ash screw 65 is connected with the shaft 64 to force the ash upwards. Particular attention is called to the inclined portion 59 of the transfer casting 57 which portion necessarily must be packed with ashes by the screw 61 before the screw 65 receives the ashes to convey them away. Consequently, the portion 59 constitutes an air seal. Furthermore, the vertical screw 65 need not be a close fit in the vertical portion of the transfer casting in that the seal portion 59 holds the ashes from falling down.

A means is provided for causing an air current beneath the annular ash conveying member and comprises a fan 66 driven by a shaft 67 in connection with the shaft of a drive motor 68. A duct 69 connects with the fan 66 and discharges into the body 10. The motor 68 is also utilized to operate the drive unit 70. This drive unit comprises a casing 71 in which the mechanism of the unit is housed. More particularly, a worm pinion 72 is mounted upon the shaft 67 and is in mesh with a worm wheel 73 free upon the shaft 46 which extends through the casing 71. A lever 74 is also free upon the shaft 46 and has a head end 75 and a tail end 76. The head end 75 is formed with openings through which a small diameter rod 77 passes so that said head end 75 is movably supported upon said rod 77 which is in turn supported on the casing 71. An adjustment screw 78 through the casing 71 is adapted to engage in the path of motion of the head end 75 so as to limit its travel as desired. An eccentric roller 79 is mounted upon the side of the worm wheel 73 and engages in an opening 80 in the lever 74. Shaft 46 passes through said opening 90. A pawl 83 mounted on the casing 71 acts against the ratchet wheel 82 limiting rotation in one direction only. A sprocket 85 is mounted upon the shaft 46 and is engaged by 50 a chain 86 extending over another sprocket 87 mounted upon the shaft 52.

The operation of the drive unit will be understood by considering that as the motor 68 operates the drive shaft 67 will rotate. This rotation is transmitted by the worm pinion 72 to the worm wheel 73. The eccentric 79 on the worm wheel 73 will cause the lever 74 to periodically oscillate back and forth. The adjusting screw 78 may be adjusted to limit the oscillation of the head end of the lever 74 to cause the tail end to move in an inverse ratio, that is, when the head end is restricted the tail end will move further. The head end of the lever 74 may move between the screw 78 and a projection 88 from the casing 71. Thus the pawl 83 will cause turning of the ratchet wheel 82, one, two, etc., number of teeth upon each oscillation depending upon the adjustment of the screw 78. A mechanism not shown on the drawings is connected to the adjusting screw 78 whereby the fan inlet passage may be adjusted for air regulation to the stoker.

The operation of the stoker may be traced from the rotation of the shaft 46 which causes oper- 75

ation of the fuel feed screw 33 and carries fuel from the hopper 34 through the fuel feed tube 15. This fuel is discharged from fuel feed tube 15 upon the grate 23. The air supply for the burning fuel may be traced from the blower 66 through the duct 69 into the lower portion of the body 10 and from there through the passages 20 and the passages 27 of the grate.

Rotation of the shaft 52 causes the operation 10 of the ash conveying screws 61 and 65. Also, rotation of the shaft 52 causes the turning of the pinion 51, the ring gear 50 and the air distributor and ash conveyor 17. As the member 17 turns, the eccentric 19 will cause the grate 23 to move 15 correspondingly and ride upon the spherical zone surface 16 so as to have a continuous wobbling gyratory crushing action in conjunction with the inner side 11^a of the furnace and a fuel bed. A feature of the crushing action is that all portions 20 of the grate move towards the wall 11^a to crush and away from the wall 11^a to cause additional material to enter between the wall 11^a and the grate. Ashes from the fire will fall through the passage 29 and some ashes may also fall through 25 openings 27 in grate 23 upon the conveying surface 21. These ashes will be forced off surface 21 by the scraper 53 as the air distributor and conveyor 17 revolves. These ashes will pass through the opening 54 and down the ash hopper 30 52. From there the ashes will be forced up through the inclined portion 59 of the transfer casting to the screw 65 and thence to the discharge not shown on the drawings. The ash accumulation within the portion 59 constitutes an 35 air seal. Another air seal exists between the portion 17 of the annular ash conveying member and the body 10, namely, air seal 30 so as to cause the draft caused by the fan 66 to only pass through the passages 20. The baffle flange 22 40 directs the air beneath the grate 23 from which it will flow through the passages 27. It should be noted that none of the ashes or fuel can possibly fall inside of the baffle 22 and thus to the bottom of the body 10 but must fall upon the conveying 45 surface 21. The action of the grate 23 will be to break up clinkering of the ash and give a continuous motion to the fuel bed thereby eliminating formation of holes in the fuel bed and impingement of air current and so preventing clinkering 50 and thus insuring the proper combustion in the stoker and a continuous shaking or working down and elimination of the ash.

While I have illustrated and described my invention with some degree of particularity, I realize that in practice various alterations therein may be made. I therefore reserve the right and privilege of changing the form of the details of construction or otherwise altering the arrangement of the correlated parts except as limited by 55 the scope of the appended claims.

Having thus described my invention what I claim as new, and desire to secure by United States Letters Patent is:—

1. In a stoker, a vertical member having a 60 spherical seat, a grate having a complementary spherical seat coacting with said first-named spherical seat for supporting said grate, and means coacting with said grate for circumferentially progressively 65 tilting said grate on said spherical seat.

2. In a stoker, a member having a spherical seat, a grate having a complementary spherical seat coacting with said first-named spherical seat for supporting said grate, and means coacting 70 with said grate for circumferentially progressive-

ly tilting said grate on said spherical seat, comprising an eccentric rotative on said member and journalled in a depending skirt on said grate.

3. In a stoker, a vertical member having a 5 spherical seat, a grate having a complementary spherical seat coacting with said first-named spherical seat for supporting said grate, and means coacting with said grate for circumferentially progressively tilting said grate on said spherical seat, comprising an eccentric rotative on 10 said member and journalled in a depending skirt on said grate, said eccentric having an outer cylindrical surface the axis of which is inclined to the axis of said vertical member, and said outer cylindrical surface engaging the inside face 15 of the wall of said skirt.

4. In an underfeed stoker, a vertically extending fuel feed tube, having a spherical seat, a grate having a complementary spherical seat coacting with said first named spherical seat for supporting said grate, and means coacting with said grate for circumferentially progressively 20 tilting said grate on said spherical seat.

5. In a stoker, a member having a spherical seat, a grate having a complementary spherical seat coacting with said first named spherical seat for supporting said grate, and means coacting with said grate for circumferentially progressively 25 tilting said grate on said spherical seat, comprising an eccentric rotative on said member and journalled in a depending skirt on said grate, said eccentric having spaced radial ribs connecting with an annular ash conveying member located beneath said grate, and means for rotating said 30 conveying member.

6. In a stoker, a member having a spherical seat, a grate having a complementary spherical seat coacting with said first named spherical seat for supporting said grate, and means coacting with said grate for circumferentially progressively 40 tilting said grate on said spherical seat, comprising an eccentric rotative on said member and journalled in a depending skirt on said grate, said eccentric having spaced radial ribs connecting with an annular ash conveying member located beneath said grate, and means for rotating said 45 conveying member, said conveying member being surrounded by an outer housing having a portion terminating in a spherical surface concentric with said first named spherical seat and the outer periphery of said grate having a spherical surface spaced inwardly from the spherical 50 surface on said housing, whereby the progressive tilting of said grate facilitates passage of ash through the space between the grate and the 55 housing.

7. In a stoker, a member having a spherical seat, a grate having a complementary spherical seat coacting with said first named spherical seat for supporting said grate, and means coacting with said grate for circumferentially progressively 60 tilting said grate on said spherical seat, comprising an eccentric rotative on said member and journalled in a depending skirt on said grate, said eccentric having spaced radial ribs connecting with an annular ash conveying member located beneath said grate, and means for rotating said conveying member, said conveying member being surrounded by an outer housing having a portion terminating in a spherical surface concentric with said first named spherical seat and the outer periphery of said grate having a spherical surface spaced inwardly from the spherical 65 surface on said housing, whereby the progressive tilting of said grate facilitates passage of ash 70

75

through the space between the grate and the housing, the periphery of the conveying member and the inner wall of said housing being connected by an air seal so that combustion air within the housing must pass between said ribs.

8. In a stoker, a member having a spherical seat, a grate having a complementary spherical seat coacting with said first named spherical seat for supporting said grate, and means coacting with said grate for circumferentially progressively tilting said grate on said spherical seat, comprising an eccentric rotative on said member and journaled in a depending skirt on said grate, said eccentric having spaced radial ribs connecting with an annular ash conveying member located beneath said grate, and means for rotating said conveying member, said conveying member being surrounded by an outer housing having a portion terminating in a spherical surface concentric with said first named spherical seat and the outer periphery of said grate having a spherical surface spaced inwardly from the spherical surface on said housing, whereby the progressive tilting of said grate facilitates passage of ash through the space between the grate and the housing, the periphery of the conveying member and the inner wall of said housing being connected by an air seal so that combustion air within the housing must pass between said ribs, and said conveying member having an annular baffle portion around said ribs to shield the conveying member from the flow of said combustion air.

9. In an underfeed stoker, a vertically extending fuel feed tube having a spherical seat at its upper end, a grate member resting upon and communicating with said tube and having a complementary spherical seat coacting with said first named seat, and means coacting with said grate for circumferentially progressively tilting said grate on said spherical seat.

10. In an under feed stoker, a vertically extending fuel feed tube having a spherical seat at its upper end, a grate member resting upon and communicating with said tube and having a complementary spherical seat coacting with said first named seat, and means coacting with said grate for circumferentially progressively tilting said grate on said spherical seat, comprising an eccentric rotative on said member and journaled in a depending skirt on said grate.

11. In an under feed stoker, a vertically extending fuel feed tube having a spherical seat at its upper end, a grate member resting upon and communicating with said tube and having a complementary spherical seat coacting with said first named seat, and means coacting with said grate for circumferentially progressively tilting said grate on said spherical seat, comprising an eccentric rotative on said member and journaled in a depending skirt on said grate, said eccentric having an outer cylindrical surface, the axis of which is inclined to the axis of said vertical member, and said outer cylindrical surface engaging the inside face of the wall of said skirt.

12. In an under feed stoker, a vertically extending fuel feed tube having a spherical seat at its upper end, an annular grate member supported upon and communicating with said tube and having a complementary spherical seat coacting with said first named seat, an outer housing having a portion terminating in a spherical surface concentric with said first named spherical seat, the outer periphery of said grate having a spherical surface spaced inwardly from the spherical surface on said housing, means for feeding fuel

through said tube to the grate, and means coacting with said grate for circumferentially progressively tilting said grate on said spherical seat whereby the fuel is agitated and the passage of the ashes through the space between the grate and the housing is facilitated.

13. In an underfeed stoker, a vertically extending fuel feed tube having a spherical seat at its upper end, a grate member resting upon and communicating with said tube and having a complementary spherical seat coacting with said first named seat, an eccentric rotatably mounted on said tube below said grate, said eccentric having an outer cylindrical surface the axis of which is inclined to the axis of said tube, a depending skirt on said grate journaled on said eccentric, and means operable to rotate said eccentric whereby said grate moves with a circumferentially, progressive tilting movement.

14. In a stoker, a member having a spherical seat, a grate having a complementary spherical seat coacting with said first named spherical seat for supporting said grate, and means coacting with said grate for circumferentially progressively tilting said grate on said spherical seat, comprising an eccentric rotative on said member and journaled in a depending skirt on said grate, said eccentric having spaced radial ribs connecting with an annular ash conveying member located beneath said grate, and means for rotating said conveying member, said conveying member being surrounded by an outer housing having a portion terminating in a spherical surface concentric with said first named spherical seat and the outer periphery of said grate having a spherical surface spaced inwardly from the spherical surface on said housing, whereby the progressive tilting of said grate facilitates passage of ash through the space between the grate and the housing, the periphery of the conveying member and the inner wall of said housing being connected by an air seal so that combustion air within the housing must pass between said ribs, and said conveying member having an annular baffle portion around said ribs to shield the conveying member from the flow of said combustion air, and means for discharging ash from said conveying member.

15. In a stoker, a vertical member having a spherical seat, a grate having a complementary spherical seat coacting with said first named spherical seat for supporting said grate, means coacting with said grate for circumferentially progressively tilting said grate on said spherical seat, said grate having a frusto conical shaped peripheral portion, and a wall above and opposed to said frusto conical shaped peripheral portion, whereby there is crushing of fuel between these parts during all upward tilting of portions of said grate.

16. In a stoker, a stationary member, a second member having a cam surface whose axis is eccentric and inclined to the normal axis of the first member and rotatably mounted on said first member, a grate, means supporting said grate over said second member in coacting relationship with said cam surface, and means for rotating said second member and thereby progressively tilting the periphery of said grate.

17. In a stoker, a stationary member, a cam rotatably mounted on said member and having its axis inclined to the normal axis of said member, a grate, means for supporting said grate superimposed over and contacting with said cam, and means for rotating said eccentric and there-

- by circumferentially progressively tilt said grate.
18. In a stoker or similar device, a grate having a frusto-conical surface, a stationary wall opposed to said surface, a bearing for said grate, and means for moving said grate on said bearing so that the axial center line of the grate travels on the surface of an imaginary cone having its apex on the same side of the base of the grate as the apex of said frusto-conical grate.
19. In a stoker or similar device, a grate having a frusto conical surface, a wall opposed to said frusto-conical surface, and means for moving said grate so that its axial center line travels on the surface of an imaginary cone having its apex on the same side of the base of the grate as the apex of said frusto conical surface, comprising a stationary member supporting said grate, a second member having a cam surface whose axis is eccentric and inclined to the normal axis of the first member, the axis of said eccentric being an ele-
- ment in said imaginary cone, said second member being rotatively mounted on said first member and coacting with said grate to tilt the same, and means for rotating said second member and therefor progressively tilting the periphery of said grate.
20. In a stoker or similar device, a grate having a frusto-conical surface, a stationary wall opposed to said surface, a bearing for said grate, means for moving said grate on said bearing so that the axial center line of the grate travels on the surface of an imaginary cone having its apex on the same side of the base of the grate as the apex of said frusto-conical grate, and said stationary wall being substantially coaxial with said imaginary cone, whereby relative movement of the grate to said wall will have a crushing effect upon material therebetween.

JAMES GUNNEL MALONE.
